UNITED STATES PATENT OFFICE.

PETER KOZBIAL, OF LATROBE, PENNSYLVANIA.

WIRE-CUTTER.

1,290,581.

Specification of Letters Patent.

Patented Jan. 7, 1919.

Application filed September 10, 1918. Serial No. 253,353.

To all whom it may concern:

Be it known that I, PETER KOZBIAL, a subject of the Emperor of Austria, residing at Latrobe, county of Westmoreland, and 5 State of Pennsylvania, have invented certain new and useful Improvements in Wire-Cutters, of which the following is a specification.

The principal object of the invention is 10 the provision of a wire cutter, preferably adapted for employment upon a gun, bayonet or other blade, for cutting either wire barriers and entanglements or similar obstacles.

15 A further object of the invention is to provide a gun, etc., with a comparatively simple, durable and effective attachment to the bayonet or the like for cutting wires with the least possible exertion, and precluding all 20 possibilities of getting out of order after an operation.

This invention, stated in general terms, 25 consists of a wire cutter embodying an eccentric for the operation of the cutter blades adapted to be readily and conveniently operated by the soldier.

30 Further objects and advantages of this invention will appear in the following description, and the novel features thereof will be particularly pointed out in the appended claims.

In the drawing forming a part of this application, like reference characters refer to 35 corresponding parts throughout the several views—

Figure 1 is a side view of the device constructed according to the present invention with the cover plate removed, and

40 Fig. 2 is a top edge view with the cover plate in position upon the device.

Referring to the drawing by numerals, 10 indicates the bayonet of a rifle, etc., upon which a sleeve 11 of the cutter 12 is seated and held in position thereon by means of 45 rods 13, 13 secured with their outer ends in the eyes 14, 14 of ears 15, 15 at the end of said sleeve and with their other ends to a gun or rifle in any convenient, well known manner forming no part of the present invention.

50 Intermediate its ends the sleeve 11 is shaped to form a casing 16, having an approximately circular base 17, the outer end of which is extended and elongated into a neck part 18, ending in a circular part 19 and point 20. This casing is adapted to be

covered by means of a similarly shaped cover 21, secured to its base part by means of a screw 22 entering the point, and of screws 23, 23 entering holes 24, 24 suitably provided in eyes or ears 25, 25 of the casing 16.

Within the casing 17 an eccentric 26 is pivotally secured as at 27 to the inner wall thereof and surrounded by a band having a neck part 28 to which is pivotally secured, 65 as at 29, a movable cutter blade 30 adapted to move within the neck part 18 and having a cutting front edge 31 adapted to work against a stationary cutter blade 32 in the front part of said neck at the point 20. Below and directly in front of said stationary blade 32 the circular part 19 is provided with a suitable slot 33 for engaging and guiding the wire to be cut between the blades. To the pivot point of the eccentric 70 is also fixedly secured a curved lever 34 for the manipulation of the eccentric and the movable blade. This arm is operated manually or by means of a pull rod 35 hooked with one of its ends into a hole 36 at the 75 outer end of said arm or curved lever 34 by means of which the parts may also be returned into their original position in which they are ready to engage another wire to be cut. It is clear that the parts may also be 80 returned into their normal position of rest by means of a suitable spring acting against the lever 34.

Having thus described my invention, what 90 I claim as new, and desire to secure by Letters Patent is:—

1. A device of the class described, comprising in combination with the bayonet of a gun or rifle, a sleeve seated upon said bayonet and adapted to be secured to the rifle, constituting a casing provided with a neck part and point, a movable cutter in 95 said neck part, an eccentric pivotally mounted in said casing to which said movable cutter is pivotally secured, a stationary cutting blade in the outer end of said casing near the point thereof, and means for operating said eccentric and movable blade for cutting a wire introduced between the cutting edges of said blades.

2. A device of the character described, comprising in combination with the bayonet of a gun or rifle, a sleeve seated upon said bayonet, means for securing said sleeve to the rifle, said sleeve comprising a semicircular bowl, an elongated neck and a circular recessed part and a point, a cover for said

sleeve, means for securing said cover to said sleeve, an eccentric pivotally mounted in said bowl and surrounded by a band having a neck, a longitudinally reciprocating cutter blade pivoted to said neck, a stationary cutter blade in said circular part above said recess therein, and means for manually operating said eccentric and movable blade for cutting a wire introduced between the blades through said recess between the cutting edges of the blades.

3. A device of the class described, comprising a sleeve constituting a hollow casing and adapted to be secured to a rifle and to be seated upon the bayonet of the same, an eccentric in said casing, a movable cutter blade mounted for longitudinal reciprocation in said casing and pivoted to said eccentric, a stationary cutting blade at the outer end of said casing, mounted for co-operation with said movable blade for cutting a wire introduced between said blades, a curved arm rigidly secured to said eccentric and an operating rod for operating said eccentric and the movable blade in and out of cutting position.

4. A device of the character described, comprising in combination with a bayonet of a gun or rifle, a hollow sleeve adapted to be seated upon said bayonet, a removable cover for said sleeve, means for securing said cover to said sleeve, an eccentric pivotally secured to the inner wall of said

sleeve, a band surrounding said eccentric and a forwardly extending neck on said band, a movable cutting blade pivotally secured to said neck, a stationary cutting blade at the outer end of said casing co-operating with said movable blade for cutting a wire introduced between said blades through a slot in the casing, and a curved arm for operating said eccentric and movable cutting blade, said arm adapted to be operated manually, and mechanical means for moving said arm into and out of its operative position.

5. A device of the character described, comprising in combination, a hollow sleeve adapted to be seated upon a bayonet and to be secured to a rifle or gun, and constituting a slotted casing, a cover for said casing, an eccentric within said casing, and a movable cutting blade secured to said eccentric, a stationary cutting blade in the casing mounted for co-operation with said movable blade for cutting a wire introduced through the slot in said casing, an arcuate arm rigidly secured to said eccentric, an operating rod for actuating said arm and eccentric and movable blade, a spring for returning said arm into its normal position, and means for securing the casing to a rifle.

In testimony whereof I have affixed my signature.

PETER KOZBIAL.
